(57) **CLAIM**

The ornamental design for a handgrip for machine elements as shown and described.

DESCRIPTION

1. Handgrip for machine elements

1.1 : Front

1.2 : Left

1.3 : Bottom

1.4 : Right

1.5 : Top

1.6 : Back perspective view

1.7 : Front perspective view

Handgrip for machine elements composed of a semi-spherical head and a frusto-conical stem, a partial curvilinear cut of said stem being provided on its frontal part. The broken

(Continued)

lines in the drawings show portions of the handgrip that form no part of the claimed design.

1 Claim, 7 Drawing Sheets
